UNITED STATES PATENT OFFICE.

THOMAS H. GRIGG, OF PHILADELPHIA, PENNSYLVANIA, ASSIGNOR TO THE GRIGG SUSPENSION TIRE COMPANY, OF CAMDEN, NEW JERSEY.

APPARATUS FOR FORMING RIMS OR THE LIKE.

SPECIFICATION forming part of Letters Patent No. 642,976, dated February 6, 1900.

Application filed January 31, 1899. Serial No. 703,983. (No model.)

To all whom it may concern:

Be it known that I, THOMAS H. GRIGG, a citizen of the United States, residing in the city and county of Philadelphia and State of 5 Pennsylvania, have invented certain new and useful Improvements in Apparatus for Forming Rims or the Like, of which the following is a full, clear, and exact description, reference being had to the accompanying drawings, forming a part of this specification.

This invention relates to an apparatus for winding flexible strips of material in close-lying convolutions or layers, and at the same time uniformly and effectively cementing the 15 same together from the innermost to the outermost layer in a manner to produce a ring or band of predetermined diameter and thickness.

The present invention has been especially 20 designed for the purpose of economizing time, labor, and expense in the manufacture of blank wheel rims or tires of wood; but obviously to the same end the machine may be used for the production of hoops, boxes, barrels, and analogous devices.

The invention, as generally stated, consists 25 in a contractile and expansible ring or former-wheel upon which the flexible strip is wound, means whereby glue or other cement 30 is progressively applied to the convolutions, and means whereby the requisite tension or pressure is applied to the strip to insure the proper formation and intimate connection and adhesion of the contiguous convolutions.

The invention consists also in means whereby the ring or former-wheel is contracted and expanded, means whereby the gluing or cementing mechanism is thrown into and out of action at the beginning and completion, 35 respectively, of the winding operation, and means whereby the pressure or tension mechanism may be thrown into and out of operation as desired, together with various novel features of construction and organization of 40 parts, which will be hereinafter fully described and claimed.

In the annexed drawings, Figure 1 is a side elevation of the apparatus as in actual operation. Fig. 1^a is a detail of the hand-lever 45 for throwing the peripheral clamping mech-

anism into and out of operation. Fig. 1^b is a sectional detail as on the line *x x* of Fig. 1. Fig. 2 is a view similar to Fig. 1, showing the parts in the position they are caused to assume upon the completion of the operation. 55 Fig. 3 is a transverse vertical section as on the line *y y* of Fig. 1. Fig. 4 is an elevation of the mechanism for operating the glue-applying roller. Fig. 5 is a sectional plan of the framework, showing the driving mechanism, the former-wheel, and the strip-guide. Fig. 6 is a view of a modification of tension device hereinafter referred to.

Numerical 1 designates a supporting-frame, and 2 a main shaft thereon geared at one end 65 with a counter-shaft 3, carrying a pulley 4, that is driven from a suitable source of power. On the opposite end of the main shaft is mounted a former-wheel 5, upon which the flexible strip 6 of wood or other suitable material is wound. This wheel comprises a series of segments 7, arranged concentrically to the shaft and connected, by means of radial arms, with an inner concentric ring 9, which is affixed to the shaft. In the present instance 70 the ring is formed on arms 10, radiating from a hub 11, fast on the shaft. Each segment is pivotally supported by two arms 12 and 13, one, 12, of which constitutes a link, while the other is extended inward tangentially to 75 the shaft, or substantially so, to constitute a lever, whereof the inner end is forked or slotted, as at 14, for the reception of a stud 15 on the end of an independently-rotatable collar or sleeve 16, fitted to the hub, whereby when said 80 collar or sleeve is partially turned the segments will be simultaneously retracted into end-to-end contact to reduce uniformly the diameter of the former-ring. A crank-lever 85 17 is fulcrumed on the end of the main shaft 90 and connected with the collar or sleeve 16, so as to facilitate the operation of turning the latter. In the extremity of one of the segments is a recess 18, which is adapted to receive the leading end of the flexible strip to 95 be wound, the upper surface of the adjacent segment (noted 7^a) being slightly beveled or reduced, as at 19, to permit the insertion of the strip in the recess. The latter segment is also provided with one or more orifices 20, 100

through which may be driven, from the under side of the segment into the strip, tacks or the like, that taking against the edges of the orifices retain the end of the strip in place. Adjacent the former-wheel is a frame 21 for the guidance of the strip, which frame in the present instance comprises a pair of parallel bars affixed to an arm or bracket 22, extending from the main frame. The leading end of the strip being secured to the wheel, as just stated, power is applied to the main shaft and the strip in consequence wound upon the wheel. During the winding operation glue or the like is progressively applied to the strip for the purpose of cementing together the successive convolutions, and at the same time peripheral pressure is applied to the strip in a manner to effect its close winding upon the wheel, and thus insure the proper curvature and adhesion of the contiguous convolutions.

The gluing mechanism is arranged directly below the wheel. It comprises a jacketed pot or vessel 22', in which the glue is contained, and a feed-roller 23, which at predetermined intervals is moved against and from the revolving strip. The roller is carried by arms 24, extending from a rock-shaft 25, journaled in bearings on one end of the vessel. One end of the shaft is extended laterally beyond the vessel and carries an inclined track-way 26, with up-projecting end pieces 27, which constitute stops for a movable weight, such as the spool 28, that is imposed on the trackway and adapted to run from end to end thereof to vary the inclination of the track-way. Normally the spool lies at the inner end of the trackway to maintain the roller depressed within the glue-pot, as represented in Fig. 2; but preparatory to the passage of the secured end of the strip above the roller the spool is forcibly struck by a depending arm 29 and knocked backward thereby sufficiently to overcome the weight of the roller, whereupon the rearward end of the trackway is depressed and the roller raised against the strip to feed the glue thereto, in which position it remains with yielding pressure until the prescribed number of convolutions have been made. During the winding of the several layers the roller is steadily depressed thereby until at or about the completion of the operation the roller is lowered sufficiently to incline the trackway toward the glue-pot, whereupon the spool, descending the incline, returns the roller to its original or idle position within the glue-pot.

The striker-arm 29 above mentioned is pivoted to a suitably-arranged lug or bracket 30 on the main frame and is connected, by means of a link 31, with a depending lever 32, the lower arm of which lies in the path of a laterally-projecting tappet-stud 33 on the segment 7^a. Hence during the rotation of the former-wheel the stud abuts against the opposing lever-arm and moves it forward, thus throw-

ing the striker-arm backward, with the effect stated.

The pressure or clamping devices illustrated in the present construction comprise a series of spring-controlled rollers 34, arranged adjacent the top and one side of the former-wheel and adapted to be thrown into and out of operation by actuation of a common hand-lever 35. The rollers are journaled in yoke-brackets 36, having outwardly-projecting shanks 37, which extend through perforated guide-lugs 38 in levers 39, so as to be longitudinally movable thereon. The shanks are each provided with a way 40, in which is fitted a screw-pin 41 in the adjacent guide-lug, so as to prevent rotation of the shank. (See Fig. 1^b.) Spiral springs 43, encircling the shanks, bear against the outer lugs and opposing studs 44 on the shanks, so as to maintain the rollers normally projected outward and against the wheel with a yielding clamping action. The levers are fulcrumed at intervals apart to a curved bar 42, which is bolted to the main frame, the outer ends of the respective levers being successively connected by links 45, whereby the entire series may be actuated simultaneously for the purpose of throwing the rollers against the strip upon the wheel, as seen in Fig. 1, or of raising them therefrom, as seen in Fig. 2. One of the levers is extended outward to constitute the hand-lever 35 above mentioned. On this hand-lever is a spring-actuated thumb-lever 46, bearing on its inner end a stud 47, adapted to register with predetermined perforations 48 in a fixed sector 49 when the hand-lever is raised or lowered, and thereby lock the latter in place. By this construction it will be seen that when the hand-lever is in the raised position the series of roller-bearing levers will radiate toward the wheel and the rollers will bear directly and forcibly against the several convolutions of the strip for the purpose stated and that when the hand-lever is depressed the rollers will be retracted from the strip. It will be observed that the outer arms of the levers are gradually lengthened from the top to the bottom lever in order to permit the requisite adjustment and throw of the rollers in respect to the former-wheel when the hand-lever is operated. The rollers are retracted when the strip has been completely wound, and a tack or the like is or may be temporarily driven into the outer extremity of the strip to secure it in place. The tacks inserted at the outset by way of the orifices in the segment 7^a are either retracted or driven into the material. The hand-lever 17 is actuated to contract the former-wheel, and the circular ring or band produced thereon is then removed. Such ring or band may be applied to a suitable lathe or turning-machine for the purpose of being channeled, planed, or worked into any desired form in cross-section, as particular requirements may demand. A ma-

chine for this purpose forms the subject of a separate application for patent filed here-with, Serial No. 703,982.

It will be understood that I do not confine my invention to the specific construction and arrangement of parts hereinbefore described, as the same may in many respects be considerably modified without departing from the fair spirit of the invention. For example, in 10 Fig. 6 I have illustrated a modification wherein the peripheral pressure or clamping rollers are dispensed with, the strip in that case being fed to the former-wheel under considerable tension exerted by opposing rollers 34^a, mounted in advance of the wheel. The first-described construction is preferable.

I claim as my invention—

1. In a machine of the character described, the combination with a shaft, of a series of 20 segments concentric therewith, an inner concentric ring affixed to the shaft, a pair of arms connecting each segment with the said ring, one of which arms constitutes a link while the other is extended inward to constitute a lever, and an independently-rotatable collar or sleeve to which the inner arms of the respective levers are pivotally connected.
2. In a machine of the character described, the combination with a shaft, of a series of 30 segments concentric therewith, an inner concentric ring affixed to the shaft, a pair of arms connecting each segment with the said ring, one of which arms constitutes a link while the other is extended inward to constitute a lever, an independently-rotatable collar or sleeve to which the inner arms of the respective levers are pivotally connected, and a crank-lever fulcrumed on the end of the shaft and connected with said collar or sleeve.
3. In a machine of the character described, the combination with a shaft, of a series of 40 segments concentric therewith, an inner concentric ring affixed to the shaft, a pair of arms connecting each segment with the said ring, one of which arms constitutes a link while the other is extended inward to constitute a lever, an independently-rotatable collar or sleeve to which the inner arms of the respective levers are pivotally connected, 45 means for retaining the end of a strip on one of said segments, whereby the strip is wound upon the segments during their rotation, and means whereby cement is applied to the successive layers or convolutions of the strip.
4. In a machine of the character described, the combination with a shaft, of a series of 50 segments concentric therewith, an inner concentric ring affixed to the shaft, a pair of arms connecting each segment with the said ring, one of which arms constitutes a link while the other is extended inward to constitute a lever, an independently-rotatable collar or sleeve to which the inner arms of the respective levers are pivotally connected, 55 means for retaining the end of a strip on one of said segments, whereby the strip is wound

upon the segments during their rotation, means whereby radially-acting pressure is applied at adjacent points upon the outer faces of the successive layers or convolutions, and 70 means whereby cement is applied to the said layers or convolutions.

5. In a machine of the character described, the combination with a segmental former, and its supporting and operating parts, of a series 75 of rollers arranged about and adjacent to the segments of said former, radial supports for said rollers, springs in said supports, a series of radial levers for said supports, the outer arms of which levers are gradually lengthened from 80 the top to the bottom lever, links connecting the arms of the successive levers, a bar to which the levers are fulcrumed, and locking means for said levers.

6. In a machine of the character described, 85 the combination with a circular former, and its supporting and operating parts, of a series of rollers arranged about and adjacent to the segments of said former, radial supports for said rollers, springs in said supports, a series 90 of radial levers for said supports, the outer arms of which levers are gradually lengthened from the top to the bottom lever, links connecting the arms of the successive levers, a bar to which the levers are fulcrumed, a 95 hand-lever forming a continuation of one of said levers, and locking means for said hand-lever.

7. In a machine of the character described, the combination with a former, and its sup- 100 porting and operating parts, of a cement-pot adjacent to the path of said former, a feeder in said pot, and means whereby the said feeder is automatically moved into contact with the work on the former at or about the 105 beginning of the winding operation and out of contact therefrom at or near the completion of the operation.

8. In a machine of the character described, the combination with a former, of a cement- 110 pot adjacent to the path thereof, a rocking trackway, cement-feeding means connected therewith, a weight on said trackway, movable from end to end thereof, and adapted when at one end of the trackway to incline the 115 same and thereby maintain the said cement-feeding means in contact with the work on the former, whereby during the progress of the work said roller and therewith the end of the trackway is depressed to permit the move- 120 ment by gravity of the weight and the consequent further depression of the trackway.

9. In a machine of the character described, the combination with a former, of a cement-pot adjacent thereto, a rock-shaft, a trackway 125 on said shaft provided with end stops, an arm on said shaft carrying a cement-feeding roller, a weight on said trackway, movable from end to end thereof, and adapted when at one end of the trackway to incline the same and thereby maintain the said roller in contact with the work on the former, whereby during the 130

progress of the work said roller and there-
with the end of the trackway are depressed
to permit the movement by gravity of the
weight and the consequent further depres-
sion of said trackway.

5 10. In a machine of the character described,
the combination with a former, of a cement-
pot adjacent thereto, a rock-shaft, a trackway
thereon provided with end stops, an arm on
10 said shaft carrying a cement-feeding roller, a
weight on said trackway movable from end
to end thereof and adapted when at one end
of the trackway to incline the same and there-
by maintain the said roller in contact with
15 the work on the former, whereby during the
progress of the work said roller and there-
with the end of the trackway are depressed
to permit the movement by gravity of the
weight and the consequent further depression
20 of said trackway, together with means where-

by the said roller is automatically moved back
on the trackway.

11. In a machine of the character described,
the combination with a former, of a cement-
pot adjacent thereto, a rock-shaft, a track- 25
way on said shaft provided with end stops, an
arm on said shaft carrying a cement-feeding
roller, a weight on said trackway, a depend-
ing striker-arm movable against said weight,
a lever, connections between the same and 30
said arm, and a stud or projection on the said
former adapted in its rotation to abut against
said lever.

In testimony whereof I have hereunto af-
fixed my signature in the presence of two sub- 35
scribing witnesses.

THOMAS H. GRIGG. [L. S.]
